UNITED STATES PATENT OFFICE.

PAUL KUEHN, OF DETROIT, MICHIGAN.

AMALGAMATING PROCESS FOR RECOVERING METALS FROM ORES.

1,231,176.

Specification of Letters Patent. Patented June 26, 1917.

Application filed December 17, 1912. Serial No. 737,278.

To all whom it may concern:

Be it known that I, PAUL KUEHN, a citizen of the United States of America, residing at Detroit, in the county of Wayne 5 and State of Michigan, have invented certain new and useful Improvements in Amalgamating Processes for Recovering Metals from Ores, of which the following is a specification, reference being had therein to 10 the accompanying drawings.

This invention relates to an improved process for recovering metals from their ores by amalgamation and its object is to provide a process whereby all of the values may 15 be recovered from comminuted ores without loss of mercury or interruption of the continuous operation of the process. My process will best be understood from a description of an apparatus by means of which it may 20 be carried out, and one form of such apparatus is shown in my Letters Patent of the United States dated March 5, 1912 and numbered 1,019,054, and a further illustration is shown in the accompanying drawing, in 25 which the figure is a vertical section through a form of such an apparatus.

As shown in the drawing, in the bottom of a receptacle 1 of a desired form and size, is placed a quantity of mercury 2 and a pipe 30 or tube 3 is suspended in this receptacle with a small space between its open lower end and the surface of the mercury. The upper end of said tube is enlarged to form a feed hopper 4 into which a pulp of finely 35 crushed ore and a flush of water is fed in any suitable manner, the bottom of the hopper being supported slightly above the plane of the upper edge of the receptacle so that when the tube and receptacle are full, the 40 pulp will have a slight head to cause it to flow over the upper edge of the receptacle.

When the pulp is fed into the hopper, it settles down in the tube and passing out of the lower end thereof, rises in the receptacle 45 and gradually overflows. In passing from the lower end of the tube through the narrow space between said end and the surface of the mercury, every part of it is brought into intimate relation with the mercury to 50 cause the fine particles of valuable metal therein to unite with the mercury and form an amalgam. The pulp is caused to flow through the receptacle by the slight difference in height between the columns of pulp 55 in the feed tube and receptacle, the base of the columns being the body of mercury in

the receptacle. This difference in height is such that the flow will be without substantial agitation but will be sufficient to keep in suspension within the liquid those particles which are of less specific gravity than the metals to be amalgamated, thus insuring the carrying off by the overflow of practically all matter except the values. To prevent material loss of mercury in the overflow, the flow should be so limited as not to materially disturb the mercury body, and thus by regulating or limiting the rate to a gentle or quiescent even radial flow from the lower end of the center column and a 60 gentle uprising movement in the outer column, all of the values are given an opportunity to separate from the other matter and settle upon the mercury, and the mercury body will not be disturbed sufficiently 65 to cause particles of mercury to be dislodged to any material extent. This rate of flow is determined by the head given the inner column over the outer column and its range 70 of variation is between a minimum which is just sufficient to keep in suspension those particles which are lighter than the metals to be amalgamated, and a maximum which is just below the point at which loss of 75 values begins.

Loss of values which is often occasioned by the fine particles of precious metal being carried over by the froth and light material which floats upon the surface of the pulp, is obviated by maintaining a hydrostatic 80 column of pulp in the feed tube from the bottom of which column the pulp seeking its level passes over the surface of the mercury and rises in the receptacle. All 85 of the froth and light matter is therefore 90 carried downward and immersed in the water, the froth being eliminated thereby, and every particle of precious metal is also 95 immersed and thus released to be precipitated upon the mercury forming the base 100 of the columns, the particles of less specific gravity than the mercury and metals amalgamating therewith being held in suspension in the fluid by the limited flow and 105 floated upwardly and over into the waste. As the pulp passes from the bottom of the center column, it flows radially in all directions into the bottom of the outer column of greater area, with an expanding movement which tends to retard its progress, and 110 the radial movement gives an even flow that prevents the formation of paths of flow or

- currents with consequent banking of sand between the paths and the carrying over of values due to the resultant increase in flow along these paths.
5. Leading from the bottom of the receptacle 1, preferably at its center, is an open ended pipe 5 which is extended laterally to the side of the device and thence upward with its open outer end 6 in the horizontal plane 10 of the level at which it is desired to maintain the mercury in the receptacle. In placing the mercury in the receptacle, the operator may pour it in until it begins to overflow from the end 6 of the pipe when he will 15 know that it is at the exact level required, and during the operation of the device, as amalgam is formed and the bulk of the mercury is increased by the addition thereto of precious metal from the pulp, it will 20 overflow from the end of said pipe, thus making the operation continuous, as it will only be necessary for the operator to put in more mercury from time to time through the feed tube 3 and if he puts in too much it 25 will not effect the operation as the surplus will simply overflow from the pipe. The necessity for discontinuing the process at intervals and cleaning out the amalgam that has been formed, is obviated by this arrangement.
- 30 Having thus fully described my invention what I claim is:—
1. A process for recovering metals from their ores which consists in providing a 35 body of mercury presenting an extended surface, maintaining a body of ore pulp upon said mercury with a quiescent expanding flow in proximity to the surface thereof without substantial agitation and without 40 materially disturbing the mercury body, and limiting the flow to a rate sufficient to keep in suspension the particles contained in the pulp which are of less specific gravity than the metals to be recovered, whereby said 45 metals are permitted to separate from the pulp and amalgamate with the mercury.
2. A process for recovering metals from their ores which consists in providing a body of mercury presenting an extended surface, 50 maintaining a body of ore pulp upon said mercury with a gentle flow of reducing velocity in proximity to the surface thereof without substantial agitation of said pulp or mercury surface, and limiting the rate 55 of flow so as to keep in suspension only those particles in the pulp which are of less specific gravity than the metals to be amalgamated.
3. A process for recovering metals from their ores which consists in providing a 60 body of mercury presenting an extended surface, maintaining columns of ore pulp having a quiescent gravity flow of reducing velocity from one to another of said columns over the surface of said body, and so limiting said flow as to keep in suspension only the particles of ore pulp which are of a less 65 specific gravity than the metals to be recovered without substantial agitation of the pulp or material disturbance of the mercury. 70
4. A process of recovering metals from their ores which consists in providing a body of mercury presenting an extended surface and maintaining thereon columns of ore pulp having a quiescent expanding gravity flow 75 from one to another in proximity to the surface of said body without material disturbance of the mercury, the rapidity of such flow being so limited as to keep in suspension in the fluid only those particles which 80 are of less specific gravity than the metals to, be recovered.
5. An amalgamating process for recovering metals from their ores which consists in providing a body of mercury having an 85 extended surface, maintaining columns of ore pulp having a quiescent gravity flow of reducing velocity in proximity to the surface of said body from the bottom of one column to the bottom of another without 90 substantial agitation of the pulp or mercury, and so limiting the rapidity of said flow as to keep in suspension the particles in said pulp which are of less specific gravity than the metal to be recovered and to prevent the 95 carrying over of particles of the mercury by the flow.
6. An amalgamating process for recovering metals from their ores which consists in providing a body of mercury, maintaining 100 concentric columns of ore pulp upon said body with a radial and expanding quiescent gravity flow from the bottom of one column to the bottom of the other over the surface of said body and so limiting the speed of 105 flow as to keep in suspension within the up-flowing column only those particles which are of less specific gravity than the metal to be amalgamated.

In testimony whereof I affix my signature 110 in presence of two witnesses.

PAUL KUEHN.
